Filed July 5, 1960, Ser. No. 61,232

Term of patent 14 years

(Cl. D33—7)

FIGURE 1 is a front perspective view of a single pedestal desk, showing our new design;

FIGURE 2 is a rear perspective view of the same; and
FIGURE 3 is a fragmentary perspective view of the leg structure.

The dominant features of the design reside in the portions shown in full lines in the drawing and are characterized by legs of angular cross section which are recessed into the side panels and spaced from the adjacent edges of the panel, in combination with the framed panels on the front and rear faces of the pedestal, substantially as shown.

The side of the desk not shown is the same in appearance as the side shown.

We claim:

The ornamental design for a single pedestal desk or similar article, substantially as shown and described.
